UNITED STATES PATENT OFFICE

CHARLES C. ARMSTRONG, OF HUNTINGTON, WEST VIRGINIA, ASSIGNOR TO THE ARMSTRONG ELECTRIC AND MANUFACTURING COMPANY, A CORPORATION OF DELAWARE

TIME-CONTROL MECHANISM FOR ELECTRIC STOVES

Original application filed August 3, 1925, Serial No. 47,830. Divided and this application filed August 30, 1926. Serial No. 132,543.

The invention relates to time control mechanism and is particularly designed to control the electric heating elements of an oven.

5 It consists in the features and combination of parts hereinafter described and particularly pointed out in the claims.

In the accompanying drawings

Figure 1 is a sectional view of an electric
10 range with my improvement in place.

Fig. 2 is a sectional view of the time control mechanism.

Fig. 3 is a rear view of Fig. 2.

Fig. 4 shows details of the mercury tube holder relating to the time control means.

Fig. 5 is a side view of the time control switch.

This specification is a division of that filed by me Aug. 3, 1925, Serial No. 47,830.

20 The time control including a clock of any standard form, the casing 66 of which is hinged at 67 to be moved into and out of one of the recesses in the main body of the stove. This recess is formed by a casing or 25 shell 68 attached to the stove body and projecting into the interior thereof in the space between one of the side walls and the oven. The flange of casing 66 is perforated at 66^x to keep the temperature within casing 68 at or near room temperature. The 30 control of the circuit which operates the

control of the circuit will be exerted by oven heaters is exerted by a tipping mercury tube 69 which has contacts therein operating in connection with the shifting body of mercury to make and break the electric circuit. The holder for this mercury tube is a sheet metal member stamped to provide spring fingers 70 for grasping the tube, a base portion 71 having an opening by which 35 said member is pivotally mounted on a stud 72 screwed to the depending part 73 of the supplemental casing 74 which carries the binding posts 75, 75* of the circuit wires 40 from which binding posts electric connection is made through wires 76 with the contacts extending into the mercury tube. This supplemental casing is secured by screws 77 to the upper side of the clock casing which 45 has an opening to receive said supplemental casing and its depending bracket portion. 50

The bracket or holder 70—71 for the mercury tube has movement on the said stud under frictional restraint of a friction washer 78 which is arranged between the head of the screw stud 79 and the part 71 of the holder, said screw being threaded into the depending part 73 of the supplemental casing 74. 55

The tube holder has a stud 80 projecting from its rear side through an opening in the part 73 of the supplemental casing or bracket and also through an opening in the back of the main casing, and this stud has inclined upper and lower inclined sides converging to a narrow edge adapted to be contacted by "on" and "off" projections 81, 82 on arms 83, 84 respectively having perforated hub portions mounted to turn on a hollow sleeve or stud 85 which fits on a stud 86 projecting from the clock mechanism through an opening in the rear wall of the casing thereof. The projections 81 and 82 are at different distances from the axis of rotation. The sleeve is held on this stud by a screw 88. The sleeve at its end has a gear wheel 89 to mesh with a gear of the clock works by which the sleeve is driven. The sleeve carries fixed thereto a dial 90, the edge of which is ratchet toothed to receive spring pawls 91-92 on the "on" and "off" arms 81, 82.

This dial plate is curved to economize space and enable it to clear the edge of the opening or recess in the main body of the casing as the clock mechanism is swung to and from place within the recess. In setting this controller the "on" arm is set at the mark on the dial 90 corresponding to the time at which cooking is to start and the "off" hand or arm is set at the time mark at which the current is to be turned off to stop cooking, it being understood that the dial is provided with hour marks corresponding to the clock face and with subdivision marks of these hours, say 12 subdivisions for each hour and the ratchet teeth correspond to these subdivisions. The dial 90 rotates with the hour hand and the current will be automatically turned on when the projection of the "on" arm tips the mercury holder by coming against the upper inclined surface of the projection 80 of the

mercury tube holder and tips the corresponding end of the mercury tube downwardly to a position in which the mercury will immerse the electric contacts thereof and cooking will continue until the dial plate 90 has rotated to the point where the projection on the "off" arm will work against the lower inclined surface of the projection 80 of the mercury tube holder and tips the corresponding end of the tube 10 upwardly to a position where the mercury will leave the contacts and break the circuit at this point. The dial 90 together with the indicator arms, the sleeve and gear for connecting with the clock works constitute a unit removable and replaceable as such.

When the time control is not desired the mercury tube can be short circuited by a switch lever 91^x pivoted on the stud of one of the terminals, i. e. 75 in the supplemental casing and adapted when thrown to one position to engage the other terminal 75^a and thus cut out electric connection with the contacts of the mercury tube, and therefore the stove may be used either with or without the time control, by 20 swinging this switch lever so as to break electrical contact with terminal 75^a or to make said contact. This switch with its terminals the mercury switch and supplemental casing constitutes a unit which can be removed from 25 or replaced on the main casing of the time control.

I claim:

1. A circuit controller including a pivoted member having a projection, arms having a 35 common pivot with projections at different distances from said pivot to engage said projection for moving said member either one way or the other according to which arm is effective, a ratchet disc, about the edge of 40 which the arms may be set, a connection from said disc to clock works for rotating said disc always in one direction, said disc serving as the driver for the arms in whatever relation they may be set, one of said arms setting the 45 said member to make and the other setting said member to break the circuit at times indicated on said disc according to the positions in which the arms are set, substantially as described.

50 2. In combination with a support, a circuit controller mounted on said support, and having a pivoted holder having a projection having upper and lower inclined surfaces, a mercury tube carried by said holder, pivotally 55 mounted arms for operating said tiltable holder, one arm having a lug projection adapted to engage one inclined surface on said holder projection to tilt the holder and tube to close the circuit, and the other arm 60 having a lug projection adapted to engage the other inclined surface to tilt the holder and tube to open the circuit, said lug projections being at different distances from the pivoted axis of said arms, a ratchet disc about 65 which said arms may be adjusted, clock works

for operating the disc, the teeth of the disc serving as the means for determining the adjusted position of and as the drive for the arms in whatever relation they may be set, and said disc with said arms serving to tilt the holder back and forth while the motion of the disc takes place always in one direction.

In testimony whereof, I affix my signature.
CHARLES C. ARMSTRONG.
